UNITED STATES PATENT OFFICE.

JAMES T. HAYS AND THOMAS C. HAYS, OF EMMITSBURG, MARYLAND.

ACETYLENE-GAS-GENERATING APPARATUS.

SPECIFICATION forming part of Letters Patent No. 609,673, dated August 23, 1898.

Application filed March 31, 1898. Serial No. 675,963. (No model.)

To all whom it may concern:

Be it known that we, JAMES T. HAYS and THOMAS C. HAYS, citizens of the United States, residing at Emmitsburg, in the county 5 of Frederick and State of Maryland, have invented certain new and useful Improvements in Acetylene-Gas Apparatus, of which the following is a specification, reference being had therein to the accompanying drawings, in 10 which—

Figure 1 represents a vertical sectional view of our apparatus, and Fig. 2 a transverse detail section of the retort containing the carbid-compartments.

15 The invention is designed to simplify and improve apparatus of this sort, rendering it safer and more effectual in operation, as more fully hereinafter set forth.

Referring to the drawings by letters, *a* designates the vertically-movable part or bell of the gasometer; *b*, the lower part of the gasometer, this lower part having double walls inclosing a suitable sealing liquid, and *c* the outlet-pipe for the gas.

25 The retort *b'*, containing the carbid-boxes, is fastened transversely of the bottom of the gasometer and is connected by a pipe *d* with the gas-space of the same, said pipe extending in through the walls of the lower section 30 of the gasometer and up through the liquid contained in the lower part thereof, said pipe *d* being provided with a valve or cock *d'* at a suitable point outside of the gasometer, whereby communication between the carbid-boxes 35 and the gasometer may be shut off. A suitable filling-pipe *e* is connected through the bottom of the gasometer with the liquid-space therein.

In the retort *b'*, the head of which is made 40 easily removable, so that the carbid may be renewed readily, are located two or more trays or boxes *f*, which are supported one above the other and are endwise and separately removable from the retorts. These trays are divided transversely into a series of compartments, the partitions being solid, so that the compartments will be water-tight from each other, the partitions, however, terminating below the upper edges of the trays, so that 45 when one compartment is filled with water

the water will flow over into the next, and so on. The innermost compartment of the upper tray is provided with a vertical tube *g*, which extends as high as the partitions in that tray and communicates through the bottom 55 of the tray with the innermost compartment of the lower tray or box.

A vertical tube *h* extends down into the water or tank space of the gasometer and is open at its lower end and provided with a valve-seat *h'*, and connecting tube *h* (at a suitable point below the water-level in the gasometer) to the gas-inlet pipe *d* is a lateral pipe *i*. Extending down through tube *h* is a rod *j*, which is provided at its lower extremity with a valve *k*, which is normally closed against seat *h'* by means of a suitable spring *l* at the upper end of rod *j* or by means of a float attached to rod *j* below valve *k*, as shown at *m* in dotted lines, or by any 60 other suitable devices. Another valve *n* is fastened to rod *j* at a point above pipe *i* and is adapted to close down upon a valve-seat *n'*, formed in tube *h* at a point below said pipe *i*, said valve *n*, as is evident, lying normally above said lateral pipe *i*, so as not to interfere with the flow of water therethrough. A tappet *o* is attached to the top of the bell *a*, directly over the rod *j*, so that when said bell falls a predetermined distance the tappet will strike upon and depress said rod *j* and open the valve *k* and let water flow into the carbid-boxes.

It will be observed that the apparatus is entirely automatic in action. As soon as a sufficient quantity of water is discharged into the carbid-box the generation of gas lifts the bell and allows valve *k* to close. Should sufficient gas be generated to endanger the apparatus, the surplus will escape through pipe *p*, which extends up through the sealing liquid between the walls of the gasometer to above the level of said liquid, its upper end communicating with the gas-space of the gasometer. The upper open end of pipe *p* is closed by a tube *q*, which depends from the upper end of the movable part *a* and extends down into the sealing liquid to a point a little above the lower edge of said bell *a*, the upper end of tube *q* being closed. 85 90 95 100

It will be observed that the tube *q* will pass out of the liquid and uncover the upper end of tube *q* at a predetermined point and thereby permit any surplus gas to escape without blowing off the top of the gasometer.

It will be observed that as the liquid passes down through pipe *d* into the carbid-receptacle the generated gas will pass up through said pipe and be thereby cooled. If it is desired to cool the gas still further, the portion of pipe *d* above pipe *i* may be removed, so that all the gas will be compelled to pass through said pipe *i* and up through tube *h*. It will be observed that the carbid in the trays will be consumed in sections, beginning with the front compartment in the upper box, then the next compartment therein, and so on, the liquid passing through pipe *g* to the rear compartment of the lower tray when the carbid in the rear compartment of the upper tray is consumed. Any number of superposed trays may be employed, as is evident. In this manner the unconsumed carbid is kept comparatively fresh until ready for immediate use.

It will be observed that should the bell of the gasometer fall to a predetermined point after all the carbid is consumed the valve *n* will seat itself upon seat *n'* and be held thereon by the pressure of the bell, and thereby prevent the tank from emptying itself through or into the carbid-retort, and should valve *d'* be inadvertently left closed, thereby preventing the gas escaping up through pipe *d*, the gas may escape up through pipe *r*, which puts the generating-chamber into communication with the gas-space of the gasometer, said pipe *r* being closed at its upper end by an inwardly-opening valve *r'*, which is in the form of a tube and normally rests upon and closes the upper

end of pipe *r*, thereby avoiding all danger of explosion in the carbid-receptacle.

Having thus fully described our invention, what we claim, and desire to secure by Letters Patent, is—

In a gas apparatus, the combination of a gas-holder consisting of an upper movable part or bell and a liquid-tank, a carbid-holder in communication with said gas-holder and the liquid-tank, a tube supported in the gas-holder and depending into the liquid and having its lower end open and provided with valve-seats *h'* and *n'*, a lateral branch pipe connected at one end to said tube and communicating at its other end with the carbid-holder, a valve-rod extending down through said tube and provided with a valve *k* at its lower end adapted to close upon the aforesaid valve-seat *h'*, means actuated independently of the movable part of the gas-holder for normally closing said valve *k* up against its seat, means whereby said valve-rod is depressed and valve *k* forced away from its seat when the movable part of the gas-holder falls, a supplemental valve *n* attached to the valve-rod above the branch-pipe connection and adapted to seat itself against said valve-seat *n'* in the tube below the branch-pipe connection when the movable part of the gas-holder falls a predetermined distance, substantially as set forth.

In testimony whereof we hereunto affix our signatures, in the presence of two witnesses, this 28th day of March, 1898.

JAMES T. HAYS.
THOMAS C. HAYS.
